UNITED STATES PATENT OFFICE.

ISAAC OSGOOD, OF CHICAGO, ILLINOIS.

FOLDING BED.

SPECIFICATION forming part of Letters Patent No. 445,629, dated February 3, 1891.

Application filed April 10, 1889. Serial No. 306,740. (No model.)

To all whom it may concern:

Be it known that I, ISAAC OSGOOD, a citizen of the United States, residing at Chicago, in the county of Cook and State of Illinois, have 5 invented certain new and useful Improvements in Folding Beds, of which I do declare the following to be a full, clear, and exact description, reference being had to the accompanying drawings, forming part of this specification.

My present invention, while applicable in part to a variety of types of folding beds, has relation more particularly to that class of folding beds wherein the main bed-frame without 15 folding at its center is swung up into a vertical inclosing casing or cabinet.

My invention consists in the various novel features of construction hereinafter described, 20 illustrated in the accompanying drawings, and particularly pointed out in the claims at the end of this specification.

Figure 1 is a view in vertical section through the bed-frame and the inclosing casing, the bed-frame being shown in open or unfolded 25 position. Fig. 2 is a view in vertical section through the inclosing casing at one side of the bed-frame, this bed-frame being shown in closed position and in side elevation. Fig. 3 is a back view of the bed-frame and inclosing 30 casing. Fig. 4 is a detail view in cross-section through one of the upper pivot-plates, through one of the swinging arms, through a guide-bar and stud or roll, showing also a portion of the bed-frame and of the inclosing 35 casing. Fig. 5 is a detail front view of the clamping-bar and its connected parts. Fig. 6 is a detail view, partly in side elevation and partly in vertical section, of the clamping-bar and its connected parts. Fig. 7 is an en- 40 larged detail view of one end of one of the straps that connect the swinging arms with the bars for moving the hinged legs. Fig. 8 is an enlarged detail view showing the manner of connecting one end of the woven-wire 45 mattress. Fig. 9 is a view in vertical section through the inclosing casing, the bed-frame being shown in side elevation and in folded position, this view illustrating modified features of my invention. Fig. 10 is a view similar to Fig. 9, showing the bed-frame turned 50 down. Fig. 11 is an enlarged detail view, partly in side elevation and partly in section,

of one of the bottom pivot-plates shown in Figs. 9 and 10. Fig. 12 is a detail perspective view of a part of the inclosing casing, 55 showing the receptacle for wash-bowl and pitcher. Fig. 13 is a view similar to Fig. 12, but showing a modified form of support for the wash-bowl and pitcher.

A designates the sides of that portion of 60 the inclosing casing into which the bed-frame proper B will be received when the bed is in folded or closed position, and A' denotes the upper portion and A² the lower portion of the main casing, which will constitute a cabinet 65 when a cabinet is to be employed.

The main bed-frame B consists of suitable side rails b and b' and suitable head and foot boards b² and b³. Between the side rails b and b', adjacent the head-board b², extends 70 the cross-bar b⁴, with which will be connected, by suitable adjusting-screws 2, the tension-bar 3, to which is attached one end of the woven-wire bed-bottom 4, the opposite end of this bed-bottom being connected to a cross- 75 bar 5, extending between the side rails b and b', by means of the clamping-bar 5^a, that is attached by screws to said cross-bar.

In order to more securely retain the end of the wire bed-bottom between the cross-bar 5 80 and clamping-bar 5^a, I prefer to form the abutting edges of these bars of irregular outline, as more particularly seen in Figs. 1 and 8, so that the wire fabric will be crimped and tightly gripped against danger of slipping. 85 The adjusting-screws 2 will pass through the tension-bar 3, and will be provided with suitable set-nuts 6, whereby the position of the tension-bar 3 will be determined in order to secure the proper tension of the woven-wire 90 bed-bottom.

I connect the side rails b and b' with the inclosing casing by means of pivotal swinging arms or links C. One of these swinging arms or links C will be attached at each side of the 95 head portion of the bed, and each of these arms or links will be provided with an eye at each end, the eyes at the lower ends of the arms C being fitted over the hubs 7, that project from the pivot-plates 8, that in the construction illustrated in Figs. 1 to 4 are shown as bolted to the inner face of the sides A of the main casing near their bottom, while the eyes in the upper ends of the swinging arms 100

C will fit over the hubs 10 of the pivot-plates 11, that are affixed to the side rails b and b' of the bed-frame at a distance from the head-board thereof. On the inner face of each of 5 the sides A of the inclosing casing is affixed a suitable guide D, within which will travel a friction roll or sleeve 20, that is carried upon a suitable stud or pin 21, projecting from the plate 22, that is attached to the ends of the 10 head-board b^2 near its upper portion, the inner flange of the guides D serving as rails for the friction rolls or sleeves 20. My object in thus connecting the bed-frame with the vertical inclosing casing by means of the pivot- 15 arms C is to enable a very shallow casing to be employed, while at the same time a very easy swinging action of the bed-frame is secured.

To the bottom of the sides A of the inclosing 20 casing, or at other convenient points, are attached, by suitable staples or eye-plates 30, the lower ends of the coiled springs E, the opposite ends of these springs being connected to a staple or eye-plate 32, that is affixed to 25 the head-board b^2 of the bed-frame about its center.

From the construction of parts as thus far defined it will be seen that if the bed be assumed to be in upright position the bed-frame 30 B will be within the sides A of the inclosing casing and the swinging arms C lie between the side rails b and b' of the bed-frame and the sides A of the inclosing casing, these bars being at such time in a position approximately 35 vertical, but slightly inclined inward, so that the weight of the bed-frame and the bedding will tend to hold the bed-frame in a normally-closed position. If now the bed-frame be swung outward, as shown by dotted lines in 40 Fig. 1, the initial turning of the bed-frame will occur by the swinging of the arms C upon the hub 7 of the pivot-plates 8; but as the friction rolls or studs 20 are free to travel along the vertical guides or ways D the weight of the bed-frame B will cause these rolls to move upward 45 along the guides or ways D, and consequently will cause the pivot-arms C to swing outward, the bed-frame at such time turning with respect to these arms upon the hubs 10 of the 50 pivot-plates 11. Hence it will be seen that as the bed-frame B is lowered from its vertical to its horizontal position the arms C will be swung into the oblique position shown in Fig. 1, while the rolls 20 will travel up the guides 55 or ways D, and as the frame is thus swung toward a horizontal position the weight of the bed-frame will be counterbalanced by the tension of the coiled springs E, which, when the bed-frame is in horizontal position, will assume 60 inclined positions.

The legs G, which sustain the foot portion of the bed-frame B, are connected by suitable hinges 40 with the bar 5, that extends between the side rails b and b' of the bed-frame, this 65 bar 5 being preferably rabbeted, as shown at 41, so that when the legs G are turned into position for use the rabbeted portion of the

bar 5 will serve not only as a direct support for the upper ends of the legs G, but the lower shoulder of the rabbeted portion of this bar 70 will serve also as a stop or brace to prevent the outward movement of the legs. This feature of thus connecting the legs G to a rabbeted bar 5 I regard as of importance, because the weight of the rear portion of the bed-frame 75 is thus relieved from the joints of the hinges, and because the outward spreading of the legs beyond an approximately vertical position is avoided. The legs G are automatically turned into position for use when the bed-frame 80 is unfolded or turned to its horizontal position by means of the bars K, the upper ends of these bars being connected to a block k , that is hinged, as at k' , to the cross-bar 45, that extends between and connects the legs 85 G, while the opposite ends of these bars K are provided with metal straps K', the eyes in the ends of which encircle the studs 50 upon the pivot-plates 51, the hubs of these pivoted plates entering suitable perforated lugs 52 90 formed upon the swinging arms C. It will be readily understood that, if desired, the straps K' may be formed in piece with the bars K if these bars are made of metal, and any other suitable means may be employed for 95 connecting the bars with the swinging arms and with the legs G. I prefer, however, to employ the straps K', and to connect these straps with the swinging arms C in the manner shown, since a hinged joint is thereby 100 provided which enables the bars to properly move in unison with the movement of the swinging arms C. Hence it will be seen that when the bed-frame is turned from its vertical to its horizontal position the outward 105 movement of the swinging arms C will cause the bars K to turn outward the bar 45, that connects the legs G, until these legs are in proper position to rest upon the floor. My object in extending the bars K in oblique 110 direction from bottom to top of the bed-frame is to insure that these bars shall lie completely under the frame, in which position they cannot be struck or tampered with, as would be the case if they extended at the 115 sides of the bed-frame beneath the side rails thereof.

In order to avoid all possibility of the accidental closing of the bed-frame after it has been swung to a horizontal position, I have 120 provided an automatic latch L, that is pivotally connected to a stud 60, affixed to the inner face of one of the sides A of the main casing near its front edge. This latch L is preferably formed with a beveled lower end 125 L, having a shoulder L', adapted to engage with a stud 61, that projects outwardly from one of the side rails of the bed-frame near its head portion, and the latch L is also by preference formed with a handle L², whereby it 130 can be thrown out of engagement when the bed-frame is to be turned into an upright position. From this construction it will be seen that when the bed is in vertical position with-

in the inclosing casing the latch will hang in the position shown in Fig. 2, and as the bed-frame is lowered to its horizontal position the stud 61 will ride against the inclined end *l* of the latch, thus forcing the latch backward until the stud 61 is above and in position to engage with the shoulder *l'*, as seen in Fig. 1 of the drawings, when the engagement of the stud 61 with the shoulder *l'* of the latch will serve to prevent any tipping upward of the bed-frame from its horizontal position. When, however, it is desired to turn upward the bed-frame, it is simply necessary to throw the latch backward, so that the end *l* of the latch shall rest upon the opposite side of the stud, after which the bed-frame can be turned up into the inclosing casing and the gravity-latch *L* will assume a position to again engage with the stud 61, when the bed-frame is next lowered.

In order to properly retain the mattress *M* within the bed-frame when this frame is turned into its vertical position, I have provided a novel construction of clamp next to be described. To the side rails or foot-board of the bed-frame is attached a journal-plate *O*, having a center perforation adapted to receive the hub 70 of the swivel-block 71, that is provided with a bearing wherein is held in a manner free to turn the clamping-bar *P*. This hub 70 will have its free end upset or riveted, and, if desired, a washer 72 may be interposed between the upset end of the hub 71 and the inner face of the bearing-plate *O*. The clamping-bar *P* has its outer end preferably bent at right angles, as shown, and downwardly curved to form the portion *P'*, that will bear upon the bedding, and at the rear end of the clamping-bar *P* is formed or attached a dog or pawl *P*², adapted to engage with the rack-bar *o'* upon the outer face of the plate *O*. The clamping-bar *P* will also be furnished with a rib or shoulder *p* to hold this bar within the swivel-block 71 against longitudinal movement. I prefer to form the pawl *P*² as a flat plate bent in the angular form shown, and to form the swivel block 71 with a groove 74 in its curved portion, so that the clamping-bar *P* can be connected to this swivel-block by merely turning the bar into such position that the pawl can be slipped into and through the open slot 74, and after the parts have been thus joined together the position of the pawl *P*² when in use will prevent the withdrawal of the clamping-bar from the swivel-block. From this construction it will be seen that when it is desired to clamp the mattress and bed-bottom so that they will be securely retained when the bed-frame is turned into its vertical position it is only necessary to depress the clamping-bar *P*, thereby causing the swivel-block 71 to turn, and the pawl *P*², by reason of its angular free end with the rack-bar *o'*, will prevent the backward movement of the clamping-bar, and will consequently cause this bar to firmly bear upon the bed-

ding. When, however, it is desired to relieve the bedding from the pressure of the clamping-bar, it is only necessary to press downwardly against the bedding the angular portion *P'* of the clamping-bar until the pawl *P*² is thrown out of engagement with the rack-bar *o'*, after which the clamping-bar *P* can be turned freely about its pivot-bolt upward and away from the bedding.

The portion *A'* of the main casing may comprise suitable chests of drawers *A*³ or other convenient receptacles; but I prefer to provide a portion of this part of the main casing with a suitable closet to receive a wash-bowl and pitcher. In order to afford a convenient means of holding the wash-bowl in position for use, I provide the inner face of the door *A*⁴ of the closet with a shelf or support *A*⁵, adapted to swing outward with the opening of the door, and thus permit much more ready access to the bowl than would be possible if the bowl remained within the closet.

Instead of connecting the shelf or support *A*⁵ rigidly to the door *A*⁴, as seen in Fig. 13 of the drawings, this shelf may be connected to the door by means of hinges, as shown in Fig. 12, so that it can be folded upward against the side of the door, in which position it will be retained by means of a suitable bottom *a*⁵. When this last form of hinged shelf is employed, I prefer to provide the inner face of the door-jamb with a suitable groove *a*⁶, adapted to receive a lug or projection *a*⁷, formed at the rear edge of the door and serving to hold the door and the shelf securely in position when the door has been opened and the wash-bowl or other article has been placed upon the shelf. This modified construction of hinged shelf is illustrated in Fig. 12 of the drawings.

In order to enable the inclosing casing or cabinet to be readily taken apart so that it can be conveniently packed or moved, I prefer to form the upper portion *A'* separate from the lower portion *A*², as illustrated in Fig. 9 of the drawings. In this construction the lower portion *A*² is provided with a ledge *A*⁶, that extends from front to back, being suitably cut away to admit the bed-frame, and the lower part of the upper portion *A'* of the casing will be set upon this ledge *A*⁶ and will be set in place thereon by suitable dowels or in other convenient manner. The side walls *A*, within which the bed-frame will be turned, will be formed of divided sections, the lower portion of these side walls being united with the lower portion *A*² of the inclosing casing and the upper portions of the side walls *A* being formed with the upper portion *A'* of the inclosing casing. From this construction it will be apparent that when it is desired to move the bed or to pack it for shipment the upper portion of the inclosing casing can be readily removed from the lower portion, thus enabling the parts to be much more readily handled and shipped. In order to afford ample space for the pillow, I prefer

to form a recess W at the back of the lower portion of the inclosing casing, this being done by setting forward the back board w of this portion of the inclosing casing, so that the necessity of removing the pillows when the bed is to be turned into folded position is avoided, and this, too, without increasing the thickness of the inclosing casing.

In Fig. 9 of the drawings the lower pivot-
10 plates 8, which serve to sustain the lower
ends of the swinging arms C, are shown as
formed in piece with the socket 50, that re-
ceives the shank 51 of the sustaining-casters
52, and in this construction, also, the pivot-
15 plates 8 are shown as formed with the ribs
54, forming sockets for hubs 55, with which
the swinging arms C are provided in this
modified construction. I regard this con-
20 struction of the pivot-plate 8 and its connec-
tion with the caster as a very advantageous
one, because it not only affords a convenient
and cheap means for attaching the caster to
the inclosing casing, but as well, also, it en-
25 ables the strain and weight of the bed-frame
to be thrown directly upon the casters and to
be relieved from the side walls of the inclos-
ing casing.

It will be readily understood that instead
of forming the plates 8 with seats or sockets
30 to receive hubs or studs on the ends of the
swinging arm C the plates might be formed
with hubs and the swinging arms with eyes
or sockets, as in the form of my invention
hereinbefore described.

35 In Fig. 9 I have also illustrated a modi-
fied form of guide-bar D, along which the
friction rolls or sleeves 20, projecting from
the head-board of the bed, will travel. In
40 this construction the guide-bars D comprise
each a single rail, over which the friction
rolls or sleeves 20 will move, and at the top
of the bars D are formed suitable seats or
sockets d, in which the sleeve or rolls 20 will
45 rest when the bed is turned to a horizontal
position. My purpose in forming the bars D
with the seats or sockets d is to avoid the
danger of the bed-frame accidentally turning
upward from a horizontal position in event
50 any considerable weight should be thrown
upon its head portion, and it is obvious that
when the sleeves or rolls 20 are within the
seats or sockets d any pressure upon the head
portion of the bed-frame tending to turn it
55 upward will be much more effectively resisted
than if straight bars D were employed, as in
the construction hereinbefore described. If
desired, however, a suitable latch L may also
be used in connection with this form of my
invention.

60 It will be readily understood that the de-
tails of construction above set out may be
varied without departing from the spirit of
my invention.

Having thus described my invention, what
65 I claim as new, and desire to secure by Let-
ters Patent, is—

1. In a folding bed, the combination, with

the main casing and the bed-frame, of pivot-
70 plates connected to the main casing for sus-
taining the bed-frame, said pivot-plates hav-
ing sockets formed integral therewith to re-
ceive suitable casters for sustaining the main
casing, whereby the weight of the bed-frame
75 will be thrown directly upon the casters, and
whereby separate plates for the attachment
of the casters are avoided, substantially as de-
scribed.

2. In a folding bed, the combination, with
the main casing and the bed-frame, of swing-
80 ing arms pivotally attached to the bed-frame,
pivot-plates fixed to the inclosing casing and
having open sockets wherein said swinging
arms will loosely rest, hinged legs pivotally
fastened to the bed-frame, and connecting-
85 rods fastened to said swinging arms and
united to said hinged legs, whereby the legs
will be extended and collapsed by the swing-
ing arms, and whereby the removal of the
bed-frame from the inclosing casing will be
90 permitted by merely lifting the swinging arms
out of the open sockets and without detach-
ing the rods that operate the hinged legs, sub-
stantially as described.

3. In a folding bed, the combination, with
the inclosing casing and the bed-frame pivot-
95 ally connected therewith and provided with
a stud 61 near its head portion, of the swing-
ing latch L, affixed to the main casing at a
distance above its pivotal connection with the
bed-frame, said latch having an inclined end
100 l and a shoulder l' arranged to depend into
the path of the stud 61, whereby when the
bed-frame is lowered to its horizontal pos-
ition the stud will ride against the inclined
end of the latch and rest upon the shoulder
105 of the latch to prevent the tipping upward of
the bed-frame until the latch is released, and
whereby when the latch is released and re-
versed it will be in position to automatically
re-engage the stud, substantially as described.

4. In a folding bed, the combination, with
the bed-frame, of a clamp for holding the
bedding in position, said clamp comprising a
ratchet-plate, a clamping-bar pivoted to said
ratchet-plate in a manner permitting it to
115 swing in vertical direction, and a pawl at-
tached to said clamping-bar and having its
end in engagement with said ratchet-plate,
said pawl serving to control the pivotal move-
ment of said clamping-bar, substantially as
120 described.

5. In a folding bed, a clamp for holding the
bedding in place, comprising a ratchet-plate,
a swivel-block pivotally connected to said
ratchet-plate, and a clamping-bar pivotally
125 held by said swivel-block, and a pawl adapted
to engage with said ratchet-plate and hold the
clamping-bar in depressed position, substan-
tially as described.

6. In a folding bed, the combination, with
the inclosing casing, of a clamp for holding
the bed-clothing in place, comprising a jour-
nal-plate O, having a rack-bar o', a swivel-
block 71, having a slot or groove 74 through-

out its length, and a clamping-bar P, provided with a pawl P², said clamping-bar being pivotally sustained within said swivel-block, substantially as described.

5 7. In a folding bed, the combination, with the inclosing casing, of a door for closing a portion of the front of said casing and a shelf hinged to said door and provided with a pro-

jecting lug, said casing being provided with a groove or way to receive said lug, substantially as described.

ISAAC OSGOOD.
